(57) **CLAIM**

The ornamental design for the container for liquids, as shown and described in the accompanying figures.

DESCRIPTION

FIG. 1 is a side view of the container for liquids according to the present invention;

FIG. 2 is a top view of the container for liquids of FIG. 1; and,

FIG. 3 is a top diagonal view of the container for liquids of FIG. 1.

1 Claim, 1 Drawing Sheet

FIG. 1

FIG. 2

FIG. 3
